SWITCH CONTROL CIRCUITS

Claude M. Hines, Pittsburgh, Pa., assignor to
The Union Switch & Signal Company, Swiss-
vale, Pa., a corporation of Pennsylvania

Application September 27, 1938, Serial No. 231,886

9 Claims. (Cl. 246—219)

My invention relates to an improved control system for the motor for operating a railway track switch, and particularly to improved means for providing overload protection for the switch 5 motor.

It has heretofore been proposed to provide an overload relay having a pick-up winding energized in accordance with the value of the current taken by the motor for operating a railway track 10 switch, this relay being arranged so that in the event the motor current is excessive the relay contacts will become picked up, thereby interrupting the circuit for energizing the switch motor and thus preventing possible injury to the 15 motor.

It has also been proposed heretofore to provide means operative on picking up of the overload relay contacts to energize a holding winding for the relay from a source in the vicinity of the 20 switch, as for instance the battery from which current is supplied to operate the switch motor. The overload relay holding winding when energized maintains the contacts of the relay picked up and thereby maintains the switch motor circuit interrupted, while means is provided which 25 is operative on reversal of the position of the switch control lever for controlling energization of the holding winding of the overload relay to effect the release of the relay contacts and thus 30 reestablish the energizing circuit for the switch motor.

It is essential to provide means for controlling the polarity of the current supplied to the overload relay holding winding so that it will be varied 35 in accordance with the direction of energization of the pick-up winding of the relay.

It is an object of my invention to provide a switch control system of the type described and incorporating means controlled by the polarize 40 switch control relay for controlling the polarity of the current supplied to the holding winding of the overload relay.

A further object of my invention is to provide 45 an improved control system of the type described in which the polarized switch control relay controls the polarity of the current supplied to the overload relay holding winding without necessitating the use of a relay separate from the control relay.

Another object of my invention is to provide 50 an improved switch control system in which on picking up of the contacts of the overload relay they will remain picked up until the switch control lever is moved from one position to the

other, whereupon the relay contacts become released and restore control of the switch to the operator.

A further object of my invention is to provide 5 an improved switch control system.

Other objects of my invention and features of novelty will be apparent from the following description taken in connection with the accompanying drawing.

In the drawing the single figure is a diagram 10 illustrating one embodiment of the improved switch control system provided by my invention.

Referring to the drawing, the reference character W designates a railway track switch which is operated by the well-known dual selector type of mechanism. In the form here shown diagrammatically, this mechanism includes a dual selector lever S which operates a link 3. When the lever S is in the normal position as shown in the drawing, link 3 connects switch W with motor M, while when the selector lever S is in the reverse position, link 3 no longer connects switch W to motor M, but instead connects the switch to a hand-throw lever H. 15 20 25

The switch W operates a motor cut-out contact 5 in accordance with the position of the switch. The contact 5 is arranged so that it engages a stationary contact 6 in all positions 30 of the switch W except the reverse position thereof, while the contact 5 engages a stationary contact 7 in all positions of the switch W except the normal position thereof.

The selector lever S operates contacts 9 and 10 in accordance with the position occupied by the lever. When the lever S is in the normal position as shown, contact 9 is out of engagement with stationary contacts 11 and 12, while the contact 10 engages stationary contacts 14 and 15. When the lever S is in the reverse or hand-throw position, the contact 10 no longer engages contacts 14 and 15, while contact 9 engages contacts 11 and 12. 35 40 45

The motor M is provided with an armature 16 and a field winding 17, while a polarized relay WR is provided for controlling the circuits for energizing the motor M. In addition, an overload relay OR is provided and is responsive to the current taken by the motor M. 50

The polarized switch control relay WR is controlled by a switch control lever L which is located at a point remote from the switch. The lever L has associated therewith contacts 19 and 20 to which are connected control wires 21 55

and 22. When the lever L is in the normal position as shown in the drawing, contact 19 connects control wire 21 to terminal B of battery 25, and contact 20 connects control wire 22 to terminal C of battery 25. When the lever L is in the reverse position, contact 19 connects control wire 21 to terminal C of battery 25, while contact 20 connects control wire 22 to terminal B of battery 25.

10 Control wire 21 is connected to contact 28 of overload relay OR, and is connected through an asymmetric unit 30 to reverse polar contact 31 of switch control relay WR. Control wire 21 is also connected through an asymmetric unit 33 to normal polar contact 35 of relay WR. The asymmetric units 30 and 33 are arranged so that one of these units will permit flow of current of one relative polarity, and the other will permit flow of current of the opposite relative polarity.

Control wire 22 is connected to one terminal of the winding of the relay WR, while the other terminal of this winding is connected by a wire 37 to a polar contact 38 of relay WR, and also to a movable contact 40 of relay OR. The contact 40 when released engages contact 28 to which is connected control wire 21 so that when the contact 40 of overload relay OR is released, a circuit is established to energize the winding of control relay WR from the control wires 21 and 22. This circuit includes control wire 21, contacts 28—40 of overload relay OR, wire 37, winding of relay WR and control wire 22.

The control relay WR has a plurality of neutral contacts 42 which are connected by wire 44 to terminal B of battery 45, while a branch of the wire 44 is connected to a reverse polar contact 46 of relay WR.

40 The movable contacts 42 when picked up engage stationary contacts 47 which are connected by a wire 49 to a normal polar contact 50 and a reverse polar contact 51 of the relay WR.

The relay WR has a polar contact 53 which is connected by a wire 54 to one brush of the motor armature 16. The polar contact 53 is adapted to engage the normal polar contact 50, and to also engage the reverse polar contact 56 which is connected by a wire 57 to contact 6 associated with the switch operated contact 5.

50 The relay WR has, in addition, a polar contact 59 which at times engages the reverse polar contact 51, and at other times engages the normal polar contact 61 which is connected by a wire 62 to stationary contact 7 associated with the switch operated contact 5.

55 The polar contact 59 is connected by a wire 64 to one terminal of a resistor 65 and of the pick-up winding 66 of overload relay OR. The other terminals of the resistor 65 and of the relay 60 pick-up winding 66 are connected by a wire 67 to a brush of the motor armature 16.

65 The resistor 65 has a positive thermal coefficient of resistance, that is, the resistance of the resistor increases as the temperature of the material of which it is constructed increases. Accordingly, on an increase in the temperature of this unit there is a reduction in the flow of current through the resistor and a corresponding increase in the flow of current in the pick-up winding 66.

70 The resistor 65 and the relay pick-up winding 66 are arranged and proportioned so that on normal flow of current in the circuit of the switch motor M insufficient current flows in the pick-up winding 66 to effect picking up of the

relay contacts. However, on an abnormal flow of current in the circuit of the motor M for an unusual period of time, the resistor 65 becomes heated and effects an increase in the flow of current in the pick-up winding 66 sufficient to effect picking up of the relay contacts.

The relay WR has a polar contact 70 which is connected by a wire 71 to one terminal of the holding winding 72 of the overload relay OR, while a branch of the wire 72 is connected to contact 14 associated with the selector lever contact 10. The contact 70 at times engages the reverse polar contact 46 to which is connected a branch of wire 44 leading from terminal B of battery 45, and at other times engages a stationary contact 74 which is connected by a wire 75 to terminal N of battery 45.

One terminal of the motor field winding 17 is connected to wire 75 and thereby to terminal N of battery 45, while the other terminal of the field winding 17 is connected to switch operated contact 5.

The overload relay OR has a movable contact 77 which is connected by a wire 78 to one terminal of the holding winding 72 of the relay OR, while a branch of this wire is connected to stationary contact 12 which at times is engaged by selector lever contact 9. The contact 77 when released engages a stationary contact 79 which is connected by a wire 80 to contact 15 which is in the normal position of the selector lever S is engaged by the contact 10.

It will be seen that when the selector lever S is in the normal position and the contacts of relay OR are released, a shunt circuit is established for the holding winding 72 of overload relay OR. This circuit is traced from one terminal of the winding 72 through wire 78, contacts 77—79, wire 80, contacts 15—10—14, and wire 71 to the other terminal of the relay winding. This shunting of the holding winding serves to render the overload relay OR slow in picking up and prevents unintended picking up of the relay contacts on a momentary overload of the switch motor.

45 The contact 77 of relay OR when picked up engages a stationary contact 82 to which is connected wire 84 leading from terminal C of battery 45. A branch of wire 84 is connected to stationary contact 11 which at times is engaged by the contact 9.

The relay OR has a movable contact 86 which becomes picked up when the contact 77 is picked up. The contact 86 is arranged so that it does not engage the contact 40 until the contact 77 55 engages contact 82, and therefore does not move contact 40 out of engagement with stationary contact 28 to interrupt the circuit of the winding of the relay WR until contact 77 is moved into engagement with contact 82 to establish a 60 circuit for energizing the holding winding 72 of relay OR.

65 It will be seen, therefore, that on picking up of the contacts of the overload relay OR a circuit for energizing the holding winding 72 is 65 established before the circuit for the winding of the relay WR is interrupted and the neutral contacts 42 of relay WR become released to interrupt the circuit for energizing the switch motor M.

70 The equipment is shown in the drawing in the position which it assumes when the switch W, the switch control lever L, and the dual selector lever S are in their normal positions, and when 75

the contacts of the overload relay OR are released.

At this time as the control lever L is in the normal position, the contacts 19 and 20 effect the supply of current of normal relative polarity from the battery 25 to the control wires 21 and 22, and as the contacts of the overload relay OR are released, a circuit is established to energize the winding of the polarized switch control relay WR with this current. This circuit includes wire 21, contacts 28-40 of overload relay OR, wire 37, winding of relay WR and control wire 22.

As the winding of relay WR is energized, the neutral contacts 42 of this relay are picked up, while the polar contacts of the relay are in their normal positions as shown. At this time, however, the circuit for energizing the motor M is interrupted as the switch operated contact 5 is out of engagement with stationary contact 7. The motor M, therefore, is not energized and the switch W remains in the normal position.

If at this time the operator wishes to effect movement of the switch W from the normal to the reverse position, he may do so by moving the control lever L from its normal to its reverse position. On this movement of the control lever L the contacts 19 and 20 interrupt the supply of current of normal relative polarity to the control wires 21 and 22 and effect the supply of current of reverse relative polarity thereto. On this reversal of the polarity of the current supplied to the control wires 21 and 22 there is a reversal in the direction of energization of the winding of the relay WR with the result that the neutral contacts 42 of this relay become released and then pick up, while the polar contacts of this relay are shifted from their normal to their reverse positions.

On movement of the polar contacts 53 and 59 of relay WR from their normal to their reverse positions a circuit is established to energize the switch motor M with current supplied from the battery 45. This circuit is traced from terminal B of battery 45 through wire 44, neutral contacts 42-47 of relay WR, wire 49, reverse polar contacts 51-59 of relay WR, wire 64, resistor 65 and holding winding 66 of relay OR in parallel, wire 67, motor armature 16, wire 54, reverse polar contacts 53-56 of relay WR, wire 57, switch contacts 6-5, motor field winding 17 and terminal N of battery 45. As a result of this energization of the switch motor M, the motor is caused to drive the switch W from the normal to the reverse position, and when the switch reaches the reverse position, switch operated contact 5 is moved out of engagement with contact 6 to thereby interrupt the circuit for energizing the switch motor M.

In similar manner, if when the switch W is in the reverse position the operator wishes to effect movement of the switch to the normal position, he may do so by moving the control lever L from its reverse to its normal position. As a result of this movement of the control lever L, current of normal relative polarity is supplied to the control wires 21 and 22 and the polar contacts of the relay WR are shifted from their reverse to their normal positions, thereby establishing a circuit for energizing the switch motor in a direction to effect movement of the switch from the reverse to the normal position.

The circuit for energizing the switch motor M includes terminal B of battery 45, wire 44, neutral contacts 42-47 of relay WR, normal polar contacts 50-53 of relay WR, wire 54, motor ar-

mature 16, wire 67, resistor 65 and pick-up winding 66 of relay OR in parallel, normal polar contacts 59-61 of relay WR, wire 62, switch contacts 7-5, field winding 17 and terminal N of battery 45.

When the switch W attains the normal position, contact 5 is moved out of engagement with contact 7, thereby interrupting the circuit for energizing the switch motor M.

This system is arranged so that in the event that during movement of the switch W from one of its positions to the other, movement of the switch is obstructed before the switch reaches the position to which it is being moved, the contacts of the overload relay OR will become picked up and will cause the circuit of the switch motor M to be interrupted and thus prevent injury to the switch motor.

For purposes of illustration, it will be assumed that the switch W is being moved from the normal to the reverse position and that movement of the switch is obstructed before the switch reaches the reverse position. In order to effect this movement of the switch to the reverse position, the control lever L is moved from its normal to its reverse position, thereby effecting the supply of current of reverse relative polarity to the control wires 21 and 22. On the supply of current of this polarity to the winding of the relay WR, the polar contacts of this relay are shifted from their normal to their reverse positions, thereby establishing the previously traced circuit to energize the switch motor M in a direction to cause the motor to move the switch W from the normal to the reverse position.

On the occurrence of the obstruction to movement of the switch there is an unusually large flow of current in the circuit of the switch motor and the resistance unit 65 becomes heated, thereby increasing its resistance and increasing the flow of current in the pick-up winding 66 of the relay OR. As a result of this increased current flow in the pick-up winding 66 the contacts of the relay OR become picked up and contact 7 is moved out of engagement with contact 5 to interrupt the shunt circuit for the holding winding 72, while contact 7 is moved into engagement with contact 82 to establish a circuit for energizing the holding winding 72. This circuit is traced from terminal C of battery 45 through wire 84, contacts 82-77 of relay OR, wire 18, holding winding 72, wire 71, reverse polar contacts 70-46 of relay WR, and wire 44 to terminal B of battery 45. As the holding winding 72 is energized, the contacts of the relay OR remain picked up after interruption of the switch motor circuit. The various parts of the system are arranged so that the force developed on this energization of the holding winding 72 assists that developed by energization of the pick-up winding 66 of relay OR.

In addition, on picking up of the contacts of relay OR, contact 86 engages contact 40 and moves it away from contact 28, thereby interrupting the circuit of the winding of the relay WR. As previously explained, however, contact 40 is not moved out of engagement with contact 28 until after contact 77 engages contact 82 to establish the circuit for the holding winding of the relay OR.

On movement of contact 40 out of engagement with contact 28 the connection between control wire 21 and wire 37 leading to a terminal of the winding of relay WR is interrupted. At this time polar contact 38 of relay WR engages re-

- verse polar contact 31. Polar contact 38 has connected thereto wire 37, while wire 21 is connected to contact 31 through the asymmetric unit 30. However, the asymmetric unit 30 is arranged to prevent flow of current of the polarity present in the control wire at the time the switch control lever is in the reverse position, and current, therefore, is not supplied through the asymmetric unit 30 to energize the winding of the relay 10 WR. Accordingly, on picking up of the contacts of the overload relay OR the circuit for energizing the winding of the switch control relay WR is interrupted and the neutral contacts 42 of this relay become released and interrupt the 15 circuit for energizing the switch motor M. The internal construction of the relay WR is such that on interruption of the circuit for energizing the winding of the relay, the polar contacts of the relay remain in their last operated position and hence remain in engagement with the 20 reverse polar contacts.

As previously explained, on picking up of the contacts of the overload relay OR, the contact 25 71 establishes a circuit for energizing the holding winding 72 of the relay OR so that the relay contacts when picked up remain picked up.

This control system is arranged so that after picking up of the contacts of the overload relay OR and resultant interruption of the switch motor circuit, the operator may effect energization of the switch motor M to return the switch W to the position from which it was being moved at the time movement of the switch was prevented.

- 35 In order to effect this control of the switch motor the control lever L is returned to its normal position, thereby interrupting the supply of current of reverse relative polarity to the control wires 21 and 22 and effecting the supply 40 of current of normal relative polarity to the control wires.

On the supply of current of normal relative polarity to the control wires 21 and 22 at a time when the polar contacts of the relay WR are in 45 their reverse positions, current is supplied to energize the winding of the relay WR by way of a circuit which includes control wire 21, asymmetric unit 30, reverse polar contacts 31-38 of relay WR, wire 37, winding of relay WR and control wire 22. As previously explained, the asymmetric unit 30 is poled to permit flow of current of normal relative polarity, and hence on the supply of current of this polarity to the control wires current is supplied to energize the winding 50 of relay WR.

On this energization of the winding of the relay WR the contact 38 is moved out of engagement with contact 31. The internal construction of the polarized relay WR, however, is such that energization of the relay winding sufficient to initiate movement of the contact 38 away from the reverse position will also cause the contact 38 to complete its movement to the normal position. Accordingly, the contact 38 will be moved out of engagement with contact 31 and into engagement with contact 35.

On movement of the contact 38 out of engagement with contact 31 and into engagement with contact 35 the supply of current to the winding of the relay WR through asymmetric unit 30 is cut off, while current of normal relative polarity supplied to the control wires 21 and 22 cannot flow through the asymmetric unit 30. Accordingly the supply of current to the winding of the

relay WR through the circuit including the polar contact 38 is cut off.

On movement of the polar contacts of the relay WR from their reverse to their normal positions the contact 70 is moved out of engagement with reverse polar contact 46 and into engagement with normal polar contact 74. On movement of the contact 70 out of engagement with contact 46 the connection from wire 71, leading from one terminal of the winding of the relay OR, to wire 44, leading to terminal B of battery 45 is interrupted, while on movement of contact 70 into engagement with contact 74 a circuit is established to connect wire 71 to wire 75 leading to terminal N of battery 45. It will 15 be seen, therefore, that on this movement of the polar contact 70 of relay WR there is a reversal in the direction of energization of the holding winding 72 of relay OR. As a result, the contacts of the relay OR become released, and contact 20 71 moves out of engagement with contact 82, thereby interrupting the circuit for energizing the holding winding 72 with the result that when the contacts of the relay become released, they will not thereafter become picked up. 25

In addition, on the release of the contacts of the relay OR contact 86 permits contact 40 to engage contact 28 to again establish connection between control wire 21 and wire 31 leading to the one terminal of the winding of the relay WR. 30 The winding of relay WR, therefore, is energized with current of normal relative polarity and the polar contacts of the relay remain in their normal positions, while the neutral contacts 42 of the relay are picked up and establish the previously traced circuit for energizing the switch motor M in a direction to effect movement of the switch W away from the reverse position to the normal position. When the switch W attains the normal position, the switch contact 5 is moved 40 out of engagement with contact 7 and interrupts the energizing circuit for the switch motor. 35

In similar manner, if, when the switch W is being moved from the reverse to the normal position, further movement of the switch is prevented before the switch reaches the normal position, the overload relay OR will operate to interrupt the circuit for energizing the winding of the control relay WR and the contacts 42 of the relay WR will become released to interrupt the 50 circuit for energizing the switch motor M.

When the switch is being moved from the reverse to the normal position, the polar contacts of the relay WR are in their normal positions as shown with the result that a circuit is established from wire 71, leading from one terminal of the winding 72 of relay OR, to wire 75 leading to terminal N of battery 45. On picking up of contact 71 of relay OR a circuit is established from terminal C of battery 45 to wire 78 leading to the other terminal of the holding winding 72 of relay OR. It will be seen that when the polar contacts of relay WR are in their normal positions the winding 72 is energized with current of a polarity opposite to that with which 65 it is energized when the polar contacts of the relay WR are in their reverse positions.

On picking up of the contacts of the relay OR contact 40 is moved out of engagement with contact 28 to thereby interrupt the connection from 70 control wire 21 to wire 37 leading to a terminal of the winding of the relay WR. In addition, at this time polar contact 38 is in engagement with normal polar contact 35, but the asymmetric unit 33 is poled to prevent flow of current of normal 75

relative polarity from wire 21 to wire 37 and no current is supplied through the unit 33 to energize the winding of the relay WR. Accordingly the neutral contacts 42 of the relay WR become released on picking up of the contacts of the overload relay OR.

If after picking up of the contacts of the overload relay OR the operator wishes to effect return of the switch to the reverse position, that is, to the position from which it was being moved at the time movement of the switch was obstructed, he may do so by returning the control lever L to the reverse position. This movement of the control lever effects the supply of current of reverse relative polarity to the control wires 21 and 22. The asymmetric unit 33 is arranged to permit flow of current of this relative polarity between wires 37 and 21 and accordingly current is supplied to energize the winding of the relay WR. On energization of the winding of the relay WR the polar contacts of this relay are shifted from their normal to their reverse position. As previously explained, on movement of contact 38 out of engagement with contact 35 the energizing circuit for the winding of relay WR is interrupted, but the internal construction of the relay is such that once movement of the polar contacts is initiated, the contacts will continue their movement until they have completed their movement to the other position. When contact 38 is moved into engagement with contact 31, no current is supplied through the asymmetric unit 30 as the unit 30 is arranged to prevent flow of current of reverse relative polarity between the wires 21 and 37.

On movement of polar contact 70 out of engagement with contact 74 the circuit from wire 71, leading from one terminal of the holding winding 72 of relay OR, to wire 75, leading to terminal N of battery 45 is interrupted, while on movement of contact 70 into engagement with contact 46 the wire 71 is connected to wire 44 leading to terminal B of battery 45. It will be seen, therefore, that on this change in the position of the polar contacts of the relay WR there is a reversal in the direction of energization of the holding winding 72 of relay OR, and the contacts of the relay OR become released and contact 77 interrupts the circuit for energizing the holding winding 72 so that the contacts of the relay do not thereafter again become picked up.

Similarly, contact 86 permits contact 40 to engage contact 28 to establish a circuit from wire 21 to wire 37 so that the winding of the relay WR is again energized by current supplied from the control wires 21 and 22. The neutral contacts of the relay WR, therefore, become picked up and complete the circuit to energize the switch motor M and cause the motor M to move the switch W to the reverse position.

From the foregoing, it will be seen that this switch control system is arranged so that on picking up of the contacts of the overload relay OR the circuit for energizing the polarized switch control relay WR is interrupted to thereby interrupt the energizing circuit for the switch motor. In addition, it will be seen that when the polar contacts of the relay WR are in either position, a circuit independent of the overload relay is established to permit energization of the winding of the relay WR with current only of a polarity effective to cause movement of the polar contacts of the relay to their other positions, and that on this movement of the relay polar contacts, the

polarity of the current supplied to the holding winding of the overload relay is reversed to thereby effect release of the contacts of the overload relay. On this release of the overload relay contacts the circuit for energizing the winding of the polarized switch control relay from the control wires is reestablished so that this relay completes the energizing circuit for the switch motor, while the polarized switch control relay may thereafter be controlled in the usual manner.

This system is also arranged so that on movement of the selector lever S to the hand-throw position the holding winding of the overload relay OR is energized so that the contacts of the overload relay become picked up and effect deenergization of the switch control relay and thus prevent energization of the switch motor as long as the selector lever S remains in the hand-throw position.

Furthermore this system is arranged so that on subsequent return of the selector lever S from the hand-throw position to the normal position the holding winding of the overload relay will continue to be energized until there is a change in the position of the switch control relay, whereupon the holding winding of the overload relay will become deenergized.

On movement of the selector lever S from the normal position to the hand-throw position, the contact 40 is moved out of engagement with the contacts 14 and 15, thereby interrupting the shunt circuit for the holding winding 72 of relay OR, while contact 9 is moved into engagement with contacts 11 and 12 and completes a circuit from terminal C of battery 45 to wire 78 leading to one terminal of the winding 72. The other terminal of the winding 72 is connected by polar contact 70 of relay WR either to wire 75, leading to terminal N of battery 45, or to wire 44 leading to terminal B of battery 45, depending upon the position occupied by the contact 70.

As the holding winding 72 of relay OR is energized, the contacts of relay OR are picked up and contact 40 is held out of engagement with contact 28 to thereby interrupt the circuit from control wire 21 to wire 37 leading to a terminal of the winding of relay WR, while contact 77 engages contact 82 to establish a stick circuit for the holding winding 72.

It will be seen that as the contacts of relay OR are picked up at a time when the selector lever S is in the hand-throw position, the circuit for energizing the winding of the switch control relay WR is interrupted, and the neutral contacts 42 of this relay are released. Accordingly the circuit for energizing the switch motor M is interrupted and will be maintained interrupted as long as the contacts of relay WR are released.

On subsequent return of the selector lever S from the hand-throw position to the normal position contact 9 is moved out of engagement with contacts 11 and 12, while contact 10 is again moved into engagement with contacts 14 and 15. On movement of contact 9 out of engagement with contacts 11 and 12 the connection established by contact 9 between wire 84, leading from terminal C of battery 45, to wire 78, leading to a terminal of holding winding 72 is interrupted, but the circuit for energizing the winding 72 is maintained by contact 77 which is picked up at this time.

On movement of contact 10 into engagement with contacts 14 and 15 wire 71 is connected to wire 80, but the shunt circuit for the holding

winding 72 is not complete as contact 77 is picked up.

If the operator wishes to regain control of the switch after movement of the selector lever S to the normal position, he may do so by moving the switch control lever L to a different position, thereby effecting reversal of the polarity of the current supplied to the control wires 21 and 22. On this reversal of the polarity of the current supplied to the control wires current is supplied to a circuit including one or the other of the asymmetric units 30 or 33, depending upon the position of the polar contacts of the relay WR, to momentarily energize the winding of the relay WR and effect movement of the polar contacts of the relay to their other positions. On this change in the position of the polar contacts of relay WR there is a reversal in the direction of energization of the holding winding 72 of relay OR, as previously explained in detail, and the contacts of this relay thereupon become released and re-establish the circuit for energizing the winding of the switch control relay WR from the control wires 21 and 22.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a switch control system, in combination, a railway track switch movable between a normal and a reverse position, a motor for moving said switch, a pair of conductors, means for supplying current of one or the other polarity to said conductors, a polarized relay controlling circuits for energizing the switch motor, an overload relay having a winding energized in accordance with the current taken by the switch motor, said overload relay having contacts which become picked up when the current taken by the switch motor exceeds a predetermined value, a circuit controlled by a contact of the overload relay for energizing the winding of the polarized relay from said pair of conductors, and circuits independent of the overload relay contacts and controlled by a polar contact of the polarized relay for also energizing the winding of the polarized relay from said pair of conductors.

2. In a switch control system, in combination, a railway track switch movable between a normal and a reverse position, a motor for moving said switch, a pair of conductors, means for supplying current of one or the other polarity to said conductors, a polarized relay controlling circuits for energizing the switch motor, said polarized relay having a polar contact movable between a normal and a reverse position in accordance with the polarity of the current supplied to the relay winding, an overload relay having a contact which becomes picked up when the current taken by the switch motor exceeds a predetermined value, a circuit controlled by the contact of the overload relay for energizing the winding of the polarized relay from said conductors, a circuit which is complete only when the polar contact of the polarized relay is in the normal position and through which current of reverse polarity only may be supplied from said conductors to the winding of the polarized relay, and a circuit which is complete only when the polar contact of the polarized relay is in the reverse position and through which current of normal polarity only may be supplied

from said conductors to the winding of the polarized relay.

3. In a switch control system, in combination, a railway track switch movable between a normal and a reverse position, a motor for moving said switch, a pair of conductors, means for supplying current of one or the other polarity to said conductors, a polarized relay controlling circuits for energizing the switch motor, an overload relay having a pick-up winding energized in accordance with the magnitude of the current taken by the switch motor, said overload relay also having a holding winding, the overload relay having contacts which become picked up on a predetermined increase in the magnitude of the current supplied to the pick-up winding or when the holding winding is energized, a circuit controlled by a contact of the overload relay for energizing the winding of the polarized relay from said conductors, and circuits independent of the contacts of the overload relay and controlled by a polar contact of the polarized relay for also energizing the winding of the polarized relay from said conductors, a contact of the overload relay being operative when picked up to establish a control circuit through which current may be supplied to the holding winding of the overload relay, a polar contact of the polarized relay controlling the polarity of the current supplied to said control circuit.

4. In a switch control system, in combination, a railway track switch movable between a normal and a reverse position, a motor for moving said switch, a pair of conductors, means for supplying current of one or the other polarity to said conductors, a polarized relay controlling circuits for energizing the switch motor, said polarized relay having polar contacts movable between a normal and a reverse position in accordance with the polarity of the current supplied to the relay winding, an overload relay having a pick-up winding and a holding winding, means for energizing the pick-up winding in accordance with the magnitude of the current taken by the switch motor, the overload relay having contacts which become picked up on a predetermined increase in the magnitude of the current supplied to the pick-up winding or when the holding winding is energized, a circuit controlled by a contact of the overload relay for energizing the winding of the polarized relay from said conductors, a circuit which is complete only when the polar contacts of the polarized relay are in their normal position and through which current of reverse polarity only may be supplied from said conductors to the winding of the polarized relay, and a circuit which is complete only when the polar contacts of the polarized relay are in their reverse positions and through which current of normal relative polarity only may be supplied to the winding of the polarized relay, a contact of the overload relay being operative when picked up to establish a control circuit through which current may be supplied to the overload relay holding winding, a polar contact of the polarized relay controlling the polarity of the current supplied to said control circuit.

5. In a switch control system, in combination, a railway track switch movable between a normal and a reverse position, a motor for moving said switch, a pair of conductors, means for supplying current of one or the other polarity to said conductors, a polarized relay controlling circuits for energizing the switch motor, said polarized relay having a polar contact movable

- between a normal and a reverse position in accordance with the polarity of the current supplied to the relay winding, an overload relay having a winding energized in accordance with the magnitude of the current taken by the switch motor and having a contact which becomes picked up when the current taken by the switch motor exceeds a predetermined value, a circuit controlled by the contact of the overload relay for energizing the winding of the polarized relay from said conductors, a first circuit which is established when the polar contacts of the polarized relay are in their normal positions and through which current may be supplied from said conductors to energize the winding of the polarized relay, and a second circuit which is established when the polar contacts of the polarized relay are in their reverse positions and through which current may be supplied from said conductors to energize the winding of the polarized relay, and a circuit controlled by the contact of the overload relay for energizing the winding of the polarized relay from said conductors, a first circuit which is established when the polar contacts of the polarized relay are in their normal positions and through which current may be supplied from said conductors to energize the winding of the polarized relay, and a second circuit which is established when the polar contacts of the polarized relay are in their reverse positions and through which current may be supplied from said conductors to energize the winding of the polarized relay, said first and second circuits each having connected in series therewith an asymmetric unit arranged to permit flow of current of a polarity effective to cause movement of the relay contacts away from the position in which the contacts complete the circuit including such asymmetric unit.
6. In a switch control system, in combination, a railway track switch movable between a normal and a reverse position, a motor for moving said switch, a pair of conductors, means for supplying current of one or the other polarity to said conductors, a polarized relay controlling circuits for energizing the switch motor, an overload relay having a pick-up winding and a holding winding, means for energizing the pick-up winding in accordance with the magnitude of the current taken by the switch motor, the overload relay having contacts which are normally released and which become picked up when the current taken by the switch motor exceeds a predetermined value or when the holding winding is energized, the overload relay contacts when released establishing a circuit for energizing the winding of the polarized relay from said pair of conductors, the overload relay contacts being operative on movement to their picked-up position to first establish a control circuit for energizing the holding winding of the overload relay and to thereafter interrupt the circuit for energizing the winding of the polarized relay from said pair of conductors.
7. In a switch control system, in combination, a railway track switch movable between a normal and a reverse position, a motor for moving said switch, a pair of conductors, means for supplying current of one or the other polarity to said conductors, a polarized relay controlling circuits for energizing the switch motor, an overload relay having a pick-up winding and a holding winding, means for energizing the pick-up winding in accordance with the magnitude of the current taken by the switch motor, the overload relay having contacts which are normally released and which become picked up when the current taken by the switch motor exceeds a predetermined value or when the holding winding is energized, the overload relay contacts when released establishing a circuit for energizing the winding of the polarized relay from said pair of conductors, the overload relay contacts being operative on movement to their picked-up position to first establish a control circuit for energizing the holding winding of the overload relay and to thereafter interrupt the circuit for energizing the winding of the polarized relay from said pair of conductors.
8. In a switch control system, in combination, a railway track switch movable between a normal and a reverse position, a motor for moving said switch, a pair of conductors, means for supplying current of one or the other polarity to said conductors, a polarized relay controlling circuits for energizing the switch motor, an overload relay having a pick-up winding and a holding winding, means for energizing the pick-up winding in accordance with the magnitude of the current taken by the switch motor, the overload relay having contacts which are normally released and which become picked up when the current taken by the switch motor exceeds a predetermined value or when the holding winding is energized, the overload relay contacts when released establishing a circuit for energizing the winding of the polarized relay from said pair of conductors, the overload relay contacts being operative on movement to their picked-up position to first establish a control circuit for energizing the holding winding of the overload relay and to thereafter interrupt the circuit for energizing the winding of the polarized relay from said pair of conductors, a first circuit controlled by a polar contact of the polarized relay and through which current may be supplied from the said conductors to the winding of the polarized relay, said circuit being complete when and only when the polar contact is in its normal position and being adapted to permit flow of current only of a polarity effective to cause movement of the relay polar contacts to their reverse position, a second circuit controlled by a polar contact of the polarized relay and through which current may be supplied from the said conductors to the winding of the polarized relay, said circuit being complete when and only when said polar contact is in its reverse position and being adapted to permit flow of current only of a polarity effective to cause movement of the relay polar contacts to their normal position.
9. In a switch control system, in combination, a railway track switch movable between a normal and a reverse position, a motor for moving said switch, a pair of conductors, means for supplying current of one or the other polarity to said conductors, a polarized relay controlling circuits for energizing the switch motor, an overload relay having a pick-up winding and a holding winding, means for energizing the pick-up winding in accordance with the magnitude of the current taken by the switch motor, the overload relay having contacts which are normally released and which become picked up when the current taken by the switch motor exceeds a predetermined value or when the holding winding is energized, the overload relay contacts when released establishing a circuit for energizing the winding of the polarized relay from said pair of conductors, the overload relay contacts being operative on movement to their picked-up position to first establish a control circuit for energizing the holding winding of the overload relay and to thereafter interrupt the circuit for energizing the winding of the polarized relay from said pair of conductors, means controlled by a polar contact of said polar relay for controlling the polarity of the current supplied to said control circuit, a first circuit controlled by a polar contact of the polarized relay and through which current may be supplied from the said conductors to the winding of the polarized relay, said circuit being complete when and only when the polar contact is in its normal position and being adapted to permit flow of current only of a polarity effective to cause movement of the relay polar contacts to their reverse position, a second circuit controlled by a polar contact of the polarized relay and through which current may be supplied from the said conductors to the winding of the polarized relay, said circuit being complete when and only when said polar contact is in its reverse position and being adapted to permit flow of current only of a polarity effective to cause movement of the relay polar contacts to their normal position.

relay and through which current may be supplied from said conductors to the winding of the polarized relay, said circuit being complete when and only when the polar contact is in its normal position and being adapted to permit flow of current only of a polarity effective to cause movement of the relay polar contacts to their reverse position, and a second circuit controlled by a polar contact of the polarized relay and through

which current may be supplied from the said conductors to the winding of the polarized relay, said circuit being complete when and only when said polar contact is in its reverse position and being adapted to permit flow of current only of a polarity effective to cause movement of the relay polar contacts to their normal position. 5
